U.S. CL. 219—211

1 Claim

ABSTRACT OF THE DISCLOSURE

A flexible heating garment in the form of a horse's leg binding. The leg binding is wrapped in a single turn about the horse's leg and has laces on opposite edges thereof to hold the fabric material in position. Electrical wiring is enclosed entirely within the fabric member and means in the form of a battery is provided in a pocket on the fabric member to apply current to the wiring to thus apply heat to the horse's leg.

BACKGROUND OF THE INVENTION

This invention, which comprises 10 items, was promulgated and developed, primarily, for the value of heat applications to the body muscles and joints of both man and beast.

Such articles which are currently on the open market, are developed and manufactured to supply heat to the human body, must be by attachment to separate and detached element for their usefulness, thereby making it dependent upon outside power sources. These outside and detached power sources are stationary. By the development of this invention, I propose to depart from the limitations and restrictions of body movements of this practice.

SUMMARY OF THE INVENTION

Therefore, the first objective of this invention is to supply heat to bodies of man and beast alike.

Another objective is to provide an independent source of power which will eliminate the limitations and restrictions to body movements.

Another objective of this invention is the consideration of its safety aspects. Regardless of the combination of materials, any transistorized applicator can be worn with complete confidence that there is no danger to life or limb to the wearer.

A further objective of this invention is to provide garments from which the maximum amount of relief can be obtained for a minimum amount of expense. Transistor batteries can be replaced for mere pennies, and the maintenance of the items may be done with a reasonable amount of care.

A still further objective of this invention is to provide garments which are convenient to the wearer. They can be worn at anytime, anywhere while at the same time, supplying the relief and comfort sought. Since no item is cumbersome or bulky, either one of them can be worn next to the flesh without public exposure.

The aforementioned objectives are in consideration for the ease and relief of body muscles and joints which are hampered by arthritis, rheumatism and other such maladies which cause discomfort, and for which heat applications can bring relief. This invention can be appreciated, especially, by the elderly.

BRIEF DESCRIPTION OF THE DRAWINGS

FIGURE 1 illustrates the Masonite base on which the circuit components of the devices of the present invention are mounted;

2

FIGURE 2 illustrates the arrangement of the circuit components on the Masonite base;

FIGURE 3 illustrates a pocket on the member of the present invention in which the apparatus shown in FIGURES 1 and 2 fits;

FIGURE 4 illustrates an enlarged view of the control for the heating member;

FIGURE 5 is a perspective view of the horse's leg binding of the present invention; and,

FIGURE 6 is a fragmentary view of the leg binding shown in FIGURE 5 illustrating its inner structure.

**DESCRIPTION OF THE PREFERRED
EMBODIMENTS**

Item I.—FIGURES 1, 2, 3 and 4 show the mechanism of this invention which is the basic principle of operation of each article included herein.

FIGURE 1 is the Masonite base attachment viewed from the under side.

FIGURE 2 shows the arrangement of the mechanism; 1 is the Masonite base attachment, in its proper place; 2 is the transistor placement; 3 is the transformer which conducts the current, and 4 is the battery which supplies the power.

FIGURE 3 is the case, or pocket, into which the mechanism fits; 5 is the pocket, or case, itself; 6 is the snap fastener to close the case and 10 is the dial, or control button.

FIGURE 4 is an enlargement of the dial, or control button, viewed from a side.

Item II.—FIGURE 5 is the leg binding for a horse; article 5 shows the placed case, or mechanism pocket; 6 shows again, the snap fastener to close the case.

FIGURE 6 is a fragmentary view of Item II, showing the inner structure of the leg binding; 7 is a similar view of the felt lining which is to be in contact with the flesh; 8 is a similar view of the asbestos inner-lining for protection; 9 is a similar view of the wiring system which supplies the heat; 14 is a similar view of the outer asbestos lining, and 13 is the exterior of the leg binding to be made of quilted material.

The leg binding shown in FIGURES 5 and 6 comprises a fabric member of a size and shape to be wrapped in a single turn about a horse's leg. Lace holes 12 are defined along opposite edges of the fabric member and these opposite edges come opposite one another when the binding is wrapped around the horse's leg. A lace 11 is provided to lace through the holes 12 and bind the edges together to hold the leg binding in position on the horse's leg. When the binding is placed on the horse's leg the binding is generally in the form of an elongated cylinder open at both ends generally as shown in FIGURE 5.

In operation the binding is wrapped around the horse's leg and secured thereto by means of the laces 11 in the lace holes 12. Current is applied to the electrical wiring 9 to apply heat to the binding and thus apply heat to the horse's leg.

I claim:

1. A leg binding for a horse comprising a fabric member of a size and shape to be wrapped in a single turn around the horse's leg in a generally elongated cylindrical configuration open at both ends, said member having a first pair of edges on the opposite sides thereof which come opposite one another when said member is wrapped around the horse's leg and a second pair of edges which form the open ends of said cylindrical configuration, adjustable means to bind said first pair of edges together to hold said member in position on said horse's leg, said adjustable means permitting the distance between said first pair of edges to be varied when said member is held in position thereby on said horse's leg, electrical wiring entirely enclosed within said member, means to apply

electrical current to said electrical wiring to heat said electrical wiring, and means defining a pocket on said fabric member, said fabric member comprising a felt layer on one side thereof to be placed in contact with the horse's flesh, a quilted layer on the other side thereof, and an insulating layer disposed between said electrical wiring in said felt and quilted layers, said adjustable binding means comprising lace holes defined along said edges and a lace adapted to pass through said holes to tie said edges together, said means to apply current to said wiring comprising batteries contained in said pocket.
